JIMMYPFOOF LOCK

Samuel Segal, Brooklyn, N. Y.

Application August 13, 1936, Serial No. 95,898

3 Claims. (Cl. 292—335)

The subject matter of the present invention is a door lock of the jimmy proof type having a vertically movable bolt comprising spaced studs adapted to removably interlock with apertured lugs of a stationary keeper fastened to the jamb or frame of the door.

The invention has for its primary object to provide in a jimmy proof lock means for automatically shifting the vertically guided bolt from an inoperative to an operative position to interlock with the apertured lugs of the fixed keeper when the door is swung to a closed position relative to the door frame.

The invention has as a further object to provide in a jimmy proof lock a toggle arrangement pivotally mounted on the vertically shiftable bolt and having means adapted to cooperate with an apertured lug of the fixed keeper for moving a pivoted latch out of the path of stop means to permit vertical displacement of the bolt in respect to the casing, and automatic means for bodily shifting the bolt, latch and toggle pursuant to release of the latch from the stop means to permit the spaced studs of the bolt to interlock with cooperating apertured lugs of the fixed keeper.

The invention also consists in certain new and original features of construction and combination of parts hereinafter set forth and as to other objects, features, advantages, the mode of operation, and manner of organization, these, inter alia, may be better understood by referring to the following description considered in connection with the accompanying drawings forming a part thereof in which:

Fig. 1 is a horizontal sectional view of the lock according to the invention, shown attached to the inner surface of a door which is shown moving in the direction of the arrow and about to close.

Fig. 2 is an inside elevational view taken on the line 2—2 of Fig. 1, particularly illustrating the bolt of the lock in an inoperative position with the pivoted latch of the bolt against a stop of the lock casing and the overhanging portion of the expanded toggle just about to strike an apertured lug of the fixed keeper.

Fig. 3 is an inside elevational view of the lock showing the position of the toggle after having struck an apertured lug of the keeper to remove or release the pivoted latch from the stop means.

Fig. 4 is a view similar to Fig. 2 however showing the bolt moved to a position where its studs interlock with the keeper when the toggle is again expanded, and where the pivoted latch is

against the stop means to prevent accidental retraction of the bolt.

Fig. 5 is a sectional view on the line 5—5 of Fig. 2.

Fig. 6 is a fragmentary front elevational view of the lock and keeper shown interlocked, particularly illustrating the position of the inner toggle in dash and dot lines.

Fig. 7 is a view similar to Fig. 2 but with the pivoted toggle removed from the bolt.

Fig. 8 is a sectional view on the line 8—8 of Fig. 2.

Fig. 9 is a sectional view on the line 9—9 of Fig. 2 and

Fig. 10 is a perspective view of the latch particularly showing the toggle mounted thereon.

As illustrated, the lock is generally denoted 10. This lock comprises a casing 11 having spaced sockets or guards 12, 13 and 14 adapted to removably receive overhanging studs 14 and 20 of a vertically shiftable bolt 16 which includes spaced and vertically disposed ribs 17 and 18 slidably guided between vertically arranged and spaced rectilinear tracks or ribs 19 and 20 projecting from wall 21 of the casing 11.

Integral with bolt 16 is lip 22 which is provided with the inclined face 23 and severally cooperating with the latter are the winged and similar arms 24 and 25 integral with and offset from annulus 26 anchored to bushing 27 to which the manipulatable knob 28 is secured. Bushing 27 is rotatably sustained in bearing 29 projecting from wall 21 of the lock casing. If knob 28 is rotated, say in the direction indicated by the arrow in Fig. 4, arms 24 and 25 will be similarly rotated.

As shown in Fig. 4, arm 25 is above the arm 24. Hence rotation of the knob in the manner suggested will ultimately cause arm 24 to strike against lip 22 and bodily raise the bolt from its operative or locked position shown in Fig. 4 to its inoperative or unlocked position shown in Fig. 2. The inclined face 23 of lip 22 permits the terminal of arm 24 to pass by lip 22 and be free thereof to assume the vertical position shown in Fig. 2, namely above the arm 25.

When knob 28 is rotated to shift the bolt to an inoperative position, the offset portion 30 of the arm 25 of the annulus 26 above lip 22 abuts leg 31 of spring 32, causing leg 31 to be displaced towards end 33 of the casing although the coiled intermediate portion of spring 32 is appropriately anchored to post 34 extending from wall 11 of the casing.

After an arm as 24 slips by and is free of in-

clined face 23 of the lip 22, leg 31 of spring 32 automatically retracts and abuts the intermediate portions 30 of the arms 24 and 25, thus holding the latter vertically in respect to the bottom wall of the casing. In such vertical relation of arms 24 and 25, terminal 35 of leg 31 is disposed between the upper arm of the annulus and wall 11.

Pivoted on bolt 16 is a latch 36. More particularly upper terminal 37 of latch 36 is pivoted on post 38 extending from the bolt 16. Latch 36 has a tongue 39 adapted to be actuated severally by the arms 24 and 25 of annulus 26. This latch is also provided with reentrant recesses 40 and 41 defining an overhanging terminal 42.

In an inoperative or open position of bolt 16 (Figs. 2 and 7), the horizontal wall of recess 41 cooperates with stop 43 to prevent downward displacement of the bolt. In a locked or open position of the bolt (Fig. 4) the horizontal wall of recess 40 cooperates with stops 43 to prevent retraction of the bolt.

Pivoted latch 36 is provided with a slot 44 adapted to loosely receive post 45 projecting from bolt 16. This post 45 serves as a fulcrum or pivot for lever 46 having its upper end 47 pivotally connected to the upper end 48 of arm or lever 49 by means of an upset rivet 50. For purposes of specification pivotally interconnected levers 46 and 49 may be considered as a toggle.

It will be noted that latch 36 is provided with a lug 51 having a laterally overhanging portion or hook 52 under which one leg 53 of spring 54 is retained. Lug 51 together with terminal portion 52 project through elongated slot 55 in the pivoted lever 46 of the toggle. The intermediate portion of spring 54 is coiled about the fulcrum post 38 which as previously pointed out 40 pivotally supports latch 36 on the bolt 16. The other leg 56 of spring 54 has its terminal retained within a recessed lug or fork 57 extending from pivoted arm 49 of the toggle.

In the position of the spring 54 illustrated in Fig. 2, legs 53 and 56 of spring 54 are diverged. In such position leg 53 abuts lug 51 of the pivoted latch 36 thus causing the walls of recess 41 to receive stop 43. Hence the bolt is prevented from being downwardly displaced. Since leg 56 of spring 54 abuts fork 57 of the pivoted arm 49 of the toggle, the terminal portion 58 of the toggle is automatically projected into the gap 59 defined by sockets or guards 12 and 13 of the casing. It follows that if the bolt is in a raised 55 or in an unlocked relation with the similar lugs 60 and 61 of the fixed keeper 62 fastened to frame 63 for the swingable door 65 on which the lock casing is mounted, terminal 42 of the pivoted latch is held against stop 43 by arm 53 of spring 54 while the other arm 56 of the latter sustains lip 58 of the toggle in an exposed position between sockets 12 and 13.

Bolt 16 may be controlled from several independent sources. As is well understood one source is from the inside face of the door since knob 28 may be turned as previously described to retract the bolt to an inoperative position. Such manipulation causes one of the arms offset from annulus 26 to first strike lip 39, causing latch 36 to pivot and be released or moved away from stop 53. Upon further rotation of the knob, the arm of the annulus releasing the latch also abuts overhanging lip 22, thus bodily shifting the bolt upwardly to its dash and dot line position shown in Fig. 4 or to the full line position shown

in Fig. 7 at which time further movement of the bolt is limited by stop lug 64. In the locked position of the bolt, stop 65' serves to limit downward displacement thereof.

The bolt may also be controlled outside of the door. In this connection a key 66 (shown in dash and dot in Fig. 1) is utilized. This key actuates a lock cylinder 67 of conventional design to rotate a stem 68 extending into a slot 69 of a bushing 70 appropriately journaled in closure plate 71 of the casing. To bushing 70 is anchored an arm 72 which serves a purpose similar to either of the arms 24 or 25 of the rotatable annulus 26, that is, if cylinder 67 is rotated, arm 72 is first caused to disengage pivoted latch 36 from the stop 43 by actuating lip 39 after which it strikes lip 22, thus bodily moving a bolt from a closed or locked to an open or unlocked position.

Now the bolt may be controlled from a source independent of the knob on the inside face of the door and from a source independent of the lock cylinder accessible at the front face of the door. This source may be considered as the keeper 62, fastened to the jamb or frame 63. Especially, however, apertured lug 60 of the keeper serves as abutment for the overhanging portion or terminal 58 of the toggle when the bolt is in an unlocked position.

With the door swinging to a closed position, (Fig. 1) terminal 58 strikes abutment 60, causing the toggle to contract and several operations to take place. The force imparted to arm 49 (see Fig. 3) of the toggle causes its companion lever 46 to tilt or pivot on fulcrum pin or post 45 and since normally one end of slot 55 of lever 46 is abutting against lug 51 of latch 36, movement of lever 46 in a direction away from stop 43, will also cause latch 36, to move away from the stop 43. In other words, if during an unlocked position of the bolt, the door is swung closed, the toggle is automatically operated by abutment 60 to cause the pivoted arms of the toggle to move towards each other and against the resistance of spring 54, and thus release or remove pivoted latch 36 away from stop 43 (Fig. 3).

With latch 36 released from the stop 43 due to the actuation and subsequent contraction of the toggle, the bolt 16 is automatically shifted downwardly to a position whereby its overhanging studs 14 and 15 interlock with the apertured lugs 60 and 61 of the fixed keeper. For this purpose, arm 75 of the spring 76 is utilized. This spring arm 75 has its end retained in a groove 77 of the fulcrum pin 38 which pivotally supports latch 36. The intermediate portion of spring 76 is coiled about a headed tube 76' removably surrounding post 78 projecting into the casing from wall 21 while the other arm 79 of spring 76 abuts an upper wall of the casing.

Having released latch 36 of the bolt from stop 43 when toggle strikes abutment 60 during closing of the door, arm 75 of spring 76 automatically moves away from spring arm 79, thus shifting the bolt downwardly from the position illustrated in Fig. 3 to the locked position shown in Fig. 4. In the locked position of the bolt, studs 14 and 15 are interlocked with the keeper, the pivoted arms 46 and 49 of the toggle are again expanded due to the automatic action of the arms of spring 54, the walls of recesses 40, however, of the latch 36 are interlocked with stop 43 and the terminal 58 of the toggle is concealed within the intermediate guard or socket 13.

Although arm 49 of the toggle is pivotally associated with lever or arm 46 thereof, the former is yieldingly retained against stop pin 80 by arm 56 of spring 54 when terminal 58 of the toggle 5 strikes the keeper. Stop pin 80 is fastened to bolt 16 and in effect serves as a stop to prevent upward displacement of arm 49 relative to the bolt. Even though arm 49 yieldingly bears against stop 80 when the toggle is contracted, arm 49 when 10 striking the keeper is slidably displaced in a direction towards post 38 to tilt its companion arm or lever 46 against the resistance of spring 54 to release the latch from the stop.

When the bolt is interlocked with the keeper, 15 it may be unlocked by either actuating the key controlled cylinder 67 exposed on the outside face of the door or by manipulating knob 28 on the inside face of the door. In either case, terminal 42 of latch 36 has its recess 40 first removed from stop 43 after which lip 22 is actuated to move the bolt upwardly, thereby shifting studs 14 and 15 out of apertured lugs 60 and 61 of the keeper.

Arms 53 of spring 54 in cooperation with hook 52 of the lug 51 projecting through slot 55 of the 20 lever 46 of the toggle comprise means for automatically moving pivoted latch 36 towards the stop 43 after catch or terminal 42 of the latch has cleared stop 43 and shortly before the bolt has reached the limit of its upward or downward 25 stroke. Thus by the present arrangement, recess 40 interlocks with one corner of stop 43 to prevent accidental upward displacement of the bolt (Fig. 4) in a locked position of the bolt, and recess 41 of terminal 42 cooperates with another 30 corner of stop 43 to prevent accidental downward displacement of the bolt in an unlocked position of the latter.

According to the invention provision has been made to prevent displacement of the bolt when 40 disposed in a locked or unlocked position. To this end, the body of the bolt 16 is provided with the spaced recesses 81 and 82 (Fig. 5). Each of these recesses is adapted to receive annular flange 87 attached to shank 88 of a manipulator or head 45 89. Shank 88 is reciprocably guided in bearing 90 of the casing and is provided with a retained and a slightly bowed spring 91 adapted to cooperate with the bearing to hold shank 88 in a set 50 position.

As illustrated in Fig. 5, the bolt is in an unlocked position. In such position recess 82 is in alignment with annular flange 87 which may be disposed in recess 82 by pushing head 89 inwardly or towards the casing. With flange 87 disposed 55 in recess 82, the bolt is prevented from displacement even though the toggle is struck against the keeper.

If the bolt of the lock is interlocked with the keeper, recess 81 is in alignment with flange 87 of the manipulator 90. If the latter is pushed inwardly, flange 87 enters recess 81 and consequently the bolt cannot be moved upwardly even though the knob 28 is manipulated from the inside and the cylinder 67 is actuated from the outside. Since the shank 88 is slidably disposed in bearing 90, it may be conveniently controlled by manipulator 89, which may be finger pressed to readily dispose flange 87 in either recess 81 or recess 82 as desired.

Attention is now particularly directed to the dash and dotted line position of the bolt and toggle as shown in Fig. 4. In this dash and dotted line position, the studs of the bolt are removed from the keeper but it is assumed that the door 70 is still closed. In this closed position of the door

although the bolt is disconnected from the keeper, it should be noted that terminal 58 is still yieldingly abutting a corner of the abutment or apertured lug 60 of the keeper. Such position of the terminal 58 is maintained even though the bolt is unlocked and the door is closed and when the latter starts to open, terminal 58 is automatically raised by spring arm 56 to an exposed position between the guards 12 and 13 as clearly illustrated in Fig. 2.

By the present invention, it is thus apparent, 10 that an improved jimmy proof lock for a door and jamb is provided wherein a vertically shiftable bolt carries toggle means cooperating with a keeper to permit automatic shifting of the bolt 15 and vertically relative to the casing thereof to permit its studs to interlock with the keeper and wherein conveniently accessible means on the casing may be manually controlled to cooperate with the bolt in its locked position to prevent shifting thereof to an unlocked position from the outside of the door.

The present invention is an improvement directed to the type of jimmy proof locks disclosed in United States Letters Patent 1,195,613 and 25 1,212,569 issued August 12, 1916 and January 16, 1937 respectively issued to Samuel Segal, the present applicant, and may be embodied in either of the embodiments disclosed thereby in each of which a vertically displaceable bolt is arranged 30 for interlocking with a fixed keeper.

As many changes may be made in the herein described embodiment and many apparently widely different embodiments of the invention may be devised without departing from the spirit 35 thereof, it is intended that all matter contained in the above description or shown in the accompanying drawings shall be interpreted as illustrative and not in a limiting sense.

I claim:

1. In a lock for cooperating with a keeper including spaced stud receiving members, said lock comprising a casing having a plurality of guards, a bolt movably guided within said casing and having studs disposed in at least a pair of said guards in an unlocked position of said bolt and adapted to be disposed in a removable interlocking relation with said members in a locked relation of said bolt, stop means, the combination with said stud receiving members, said guards, said bolt, and said stop means; a latch pivoted to said bolt, a toggle pivotally supported on said bolt and comprising pivotally connected arms, resilient means for spreading said arms to permit a portion thereof to be exposed between a pair of said spaced guards in an unlocked position of said bolt and to disengageably retain said latch against said stop means, said exposed portion adapted to strike one of said stud receiving members for actuating said toggle to disengage 50 said latch from said stop means, and spring means for shifting said bolt to dispose said studs in a removable interlocked relation with said stud receiving members, said resilient means cooperating to shift said latch into engagement 55 with said stop means pursuant to interlocking of said studs and members to preclude retraction of said bolt.

2. In a lock for cooperating with a keeper including exposed stud receiving members, said lock comprising a casing having a plurality of guards, a bolt movably guided within said casing and having studs disposed in at least a pair of said guards in an unlocked position of said bolt and adapted to be disposed in a removable inter- 75

locking relation with said members in a locked relation of said bolt, stop means, the combination with said stud receiving members, said guards, said bolt, and said stop means; a latch pivoted to said bolt, a toggle pivotally supported on said bolt and comprising pivotally connected arms, resilient means for spreading said arms to permit a portion thereof to be exposed between a pair of said guards in an unlocked position of 5 said bolt and to disengageably retain said latch against said stop means, said exposed portion adapted to strike one of said stud receiving members for actuating said toggle to disengage said latch from said stop means, and spring 10 means for shifting said bolt to dispose said studs in a removable interlocked relation with said stud receiving members, said resilient means cooperating to shift said latch into engagement with said stop means pursuant to interlocking of 15 said studs and members to preclude retraction of said bolt, and rotatable means for disengaging said latch from said stop means and for retracting said bolt to dispose said studs in an unlocked relation with said members.

20 3. In a lock for cooperating with a keeper including spaced stud receiving members, said lock comprising a casing having a plurality of guards, a bolt movably guided within said casing and having studs disposed in at least a pair of said

guards in an unlocked position of said bolt and adapted to be disposed in a removable interlocking relation with said members in a locked relation of said bolt, stop means, the combination with said stud receiving members, said guards, 5 said bolt, and said stop means; a latch pivoted to said bolt, a toggle pivotally supported on said bolt and comprising pivotally connected arms, resilient means for spreading said arms to permit a portion thereof to be exposed between a pair of said guards in an unlocked position of 10 said bolt and to retain said latch against said stop means, said exposed portion adapted to strike one of said stud receiving members and be concealed within said casing and adapted to 15 actuate said toggle to disengage said latch from said stop means, spring means for shifting said bolt to dispose said studs in a removable interlocked relation with said stud receiving members, said resilient means cooperating to shift said latch into engagement with said stop means pursuant to interlocking of 20 said studs and members to preclude retraction of said bolt, and rotatable means for disengaging said latch from said stop means and for retracting said bolt to 25 dispose said studs in an unlocked relation with said members and for exposing said portion between said pair of guards.

SAMUEL SEGAL.
